UNITED STATES PATENT OFFICE.

LUDY W. WOOLWINE, OF HAWKS NEST, WEST VIRGINIA, ASSIGNOR OF ONE-HALF TO
DANIEL BOONE, OF HAWKS NEST, WEST VIRGINIA.

SAFETY CRANKING DEVICE.

1,168,694.

Specification of Letters Patent. Patented Jan. 18, 1916.

Application filed October 13, 1914. Serial No. 866,495.

To all whom it may concern:

Be it known that I, LUDY W. WOOLWINE, a citizen of the United States, residing at Hawks Nest, in the county of Fayette and 5 State of West Virginia, have invented certain new and useful Improvements in Safety Cranking Devices, of which the following is a specification.

My invention relates to safety cranking 10 devices for internal combustion engines.

The primary object of my invention resides in the provision of a novel cranking device in which the crank arm is rotatably mounted on the shaft and the handle is rotatably mounted on the arm, the arm having novel means associated therewith for holding the handle in a rigid position with respect to the shaft, the connecting means being automatically operated upon back-firing 20 of the engine for releasing the arm and handle portion of the crank.

Another object of my invention resides in the provision of a novel means for rotatably mounting the handle on the arm, the handle 25 having novel means associated with one end thereof for engagement with the disconnecting means for establishing a rigid mounting of the handle with respect to the arm and shaft.

A still further object of my invention resides in the provision of a novel means for rotatably and removably mounting the cranking arm on the shaft, the latter being positioned about a ratchet rigidly carried by 35 the shaft which has associated therewith the disconnecting means for establishing a rigid connection of the arm and handle to the shaft.

A still further object of my invention resides in the provision of a device of the character described that is simple in construction, efficient in operation and one that can be manufactured and placed on the market at a minimum cost.

Other objects as well as the nature, characteristic features and scope of my invention will be more readily understood from the following description taken in connection with the accompanying drawings and pointed out in the claims forming a part of this specification.

In the drawings:—Figure 1 represents a side elevational view of my invention; Fig. 2 represents a vertical sectional view of my

invention taken on the line 2—2 of Fig. 1; 55 Fig. 3 represents a fragmentary sectional view of the outer end of the crank arm showing especially the means for connecting the handle to the arm and the disconnecting means associated therewith; Fig. 4 60 represents a fragmentary sectional view of the inner end of the crank and arm showing the novel means for connecting the same to the crank shaft.

Referring more particularly to the drawings in which similar reference numerals designate like or corresponding parts throughout the different views, I provide a crank shaft 1, the latter being suitably and rotatably mounted in a position of alignment with an engine shaft, not shown, and has a clutch head 2 formed on one end thereof for engagement with a similarly formed clutch head on the engine shaft, not shown, and which shaft 1 has its opposite end reduced, the inner part of the reduced portion adjacent the shoulder being squared as at 3 and the extreme terminal of the reduced portion being screw threaded as at 4 for a purpose to be hereinafter described. 65 Rotatably and removably mounted on the outer end of the shaft 1 is my improved cranking device including essentially an arm portion 5 and a handle portion 6. The arm 5 in this instance is enlarged and bifurcated at one 70 end thereof to form spaced parallel extensions 7, the latter being provided with alining openings for engagement with the shaft 1, the squared portion of the latter being also engaged by a ratchet wheel 8 which is 75 arranged between the extensions and which ratchet wheel is prevented from movement 80 on the shaft by means of a suitable jam nut 9, the latter being positioned within the opening in one of the extensions and screw 85 threaded about the reduced end 4 of the shaft, the inner edge of which nut bears against the wheel 8 and prevents movement 90 thereof. The opposite end of the arm 5 is cut away on its surface and is provided with an opening adjacent the extreme upper edge 95 thereof through which is rotatably mounted the rod 10, the latter having a handle 6 rigidly connected thereto; the rod 10 being squared adjacent its inner end as at 11 to 100 receive the ratchet wheel 12, the wheel being arranged in close relation with the surface of the arm 6 and held on the shaft by 105

means of a nut 13, the latter being screw threaded on the extreme inner terminal of the shaft.

For the purpose of preventing the rotation of the handle and for establishing a rigid connection between the handle 6 and the shaft 1, I have pivotally mounted a pawl 14, on the arm 5, the inner end of which pawl is held in engagement with the ratchet by means of a suitable leaf spring 15, the ratchet being also engaged at a point substantially diametrically opposite the point of engagement of the pawl 14 by a trip lever 16, the latter being pivotally mounted at a point substantially intermediate its ends by a suitable fastening device preferably a pin 17, the latter extending through an opening 18 provided in the arm, and which lever has its inner end beveled as at 19 and arranged in engagement with one of the teeth of the ratchet wheel 12. The trip lever 16 is held in yielding engagement with a suitable abutment 20 formed integral with the arm, the lever engaging the abutment at a point adjacent its extreme lower end and which end is held in yielding engagement with the abutment by means of a suitable elastic element, preferably a coil spring 21, the upper end of the lever being also engaged on its opposite side by means of a suitable elastic element, preferably a coil spring 22 for facilitating the yielding engagement of the lever 16 with the abutment 20. Extending centrally and longitudinally through the arm is a bore 23 in which is slidably mounted a rod 24, the lower end of which rod is beveled as at 25 and arranged in engagement with the teeth on the ratchet-wheel 8. The upper end of the rod 24 is normally arranged in engagement with the lower end of the trip lever 16 and establishes a rigid connection between the handle 6 and the shaft 1 when it is desired to crank the engine.

In order to facilitate the disengagement of the beveled portion 25 of the rod from the teeth of the ratchet wheel 8 when the trip lever 16 has been removed from engagement with the upper end thereof by back-firing of the shaft, I have enlarged the bore adjacent the upper end thereof and disposed about the rod in the enlarged portion of the bore a suitable elastic element preferably a coil compression spring 26, the respective ends of which bear against the shoulder formed by enlarging the bore and a pin 27 which extends transversely through the rod adjacent the upper end thereof. In order to replace the rod 24 in engagement with the trip lever 16, I have pivotally mounted a lever 28 within a recess 29 formed in the handle, the inner end of which lever being pivotally connected by means of a suitable fastening element 30 to a point adjacent the extreme upper terminal of the

rod 24. It can be seen by pressing upwardly on the lever, the rod 24 is forced downwardly and the springs 21 and 22 will normally place the trip lever 16 in a position in substantial alinement above the rod 70 whereupon the same is released and will engage the lower end of the lever. A casing 31 formed of substantial similar material as the arm 5 is removably secured by means of suitable fastening devices about the cut 75 away portion on the upper end of the arm, the casing inclosing and protecting the mechanism about this point.

The operation of my invention is as follows: Assuming that the clutch head 2 on the crank shaft 1 has been placed in engagement with the clutch head of an engine shaft, not shown, the handle 6 is cranked by one hand of the user and rotated, a rotary movement also being imparted to the 80 crank shaft 1 due to the substantial rigid connection between the handle and the crank shaft. Should the engine back-fire during the rotation of the crank, the slight jar which is first imparted to the handle 6 will 85 slightly rotate the handle 6 in a reversed direction causing the trip lever 16 to be removed from engagement with the upper end of the rod 24, whereupon the coil compression spring 26 bearing against the pin 27 90 will lift the beveled end 25 of the rod out of engagement with the ratchet wheel 8 and allow the shaft 1 to rotate in a reversed direction without injuring the hand of the operator. In order to replace the rod all 95 that is necessary is to engage the handle lever 28 and pull the same upwardly causing the pin 27 to compress the coil spring and allow the beveled end to engage the teeth of the ratchet, during which operation 100 the coil springs 21 and 22 will place the trip lever 16 in engagement with the abutment 20 and in a position of alinement above the upper end of the rod 23 whereupon the handle 28 is released and the upper end of the rod allowed to engage the lower end of the lever as clearly shown in Fig. 3 of the drawings. It is thought to be obvious that due to the pawl 14 and the spring 15 rotary 105 movement of the handle 6 is prevented when the engine is being cranked in the usual manner.

Although I have shown and described the preferred embodiment of my invention, I desire to be understood that I am not limited to the exact details shown, however, great stress is laid upon the crank arm and the means for mounting the handle and arm, the latter having a disconnecting means, including the rod 24 and lever 16 for automatically disconnecting the handle and arm when the engine back-fires.

From the above description taken in connection with the accompanying drawings, it can easily be seen that I have provided a 110 115 120 125 130

device that is simple in construction, containing but a few simple parts that can be cheaply manufactured and assembled and when assembled can be placed upon the market and sold at a minimum cost.

It will be understood that the above description and accompanying drawings comprehend only the general and preferred embodiment of my invention and that various minor changes in detail of construction, proportion and arrangement of the parts may be made within the scope of the appended claims and without sacrificing any of the advantages of my invention.

Having thus fully described my invention, what I claim as new and desire to secure by Letters Patent, is:—

1. In a safety cranking device for internal combustion engines, the combination with a shaft, of a crank arm rotatably mounted thereon, gripping means rigidly mounted on the shaft, a handle rotatably mounted on the arm, gripping means rigidly mounted on the handle, slidably mounted engaging means associated with said arm and in removable engagement with the gripping means on the shaft, and tripping means pivotally mounted on the arm and in engagement with the gripping means on the handle and the slidably engaging means actuatable by the reverse movement of the handle due to back-firing of the engine to release the slidably engaging means from the gripping means on the shaft.

2. In a safety crank device for internal combustion engines, the combination with a shaft, of a crank arm rotatably mounted thereon, a handle rotatably mounted on the arm, gripping means carried by the shaft and the handle, slidably mounted means associated with the arm for removable engagement with the gripping means on the shaft, tripping means pivotally mounted on the arm for removably holding the said engaging means in position and for engagement with the gripping means on the handle, and actuatable upon back-firing of the engine to release the slidably engaging means from the gripping means on the shaft, means associated with the arm and in connection with the slidably mounted engaging means for resetting the engaging means, and means

for resetting the tripping means after the rod has been reset.

3. In a safety cranking device for internal combustion engines, the combination with a shaft, of a crank arm rotatably mounted thereon, a ratchet wheel rigidly mounted on said shaft, a handle rotatably mounted on the arm, a ratchet wheel rigidly carried by said handle, a rod slidably mounted on said arm and in removable engagement with the ratchet wheel on the shaft, a trip lever pivotally mounted on the arm and in engagement with the ratchet wheel on the handle and the rod and actuatable by the reverse movement of the handle due to back-firing of the engine to release said rod from the ratchet wheel on the shaft, a hand lever pivoted on the arm and pivotally connected to the rod for returning the rod into engagement with the ratchet wheel on the shaft, and resilient means associated with the arm and the trip lever for returning the trip lever into engagement with the ratchet wheel on the handle and the rod when the rod has been reset.

4. In a safety device for internal combustion engines, the combination with a shaft, of a crank arm rotatably mounted thereon, a ratchet wheel rigidly mounted on the shaft, a handle rotatably mounted on the arm, a ratchet wheel carried by the handle, means for preventing movement of said ratchet wheel in one direction, a rod slidably mounted in said arm and in removable engagement with the ratchet wheel on the shaft, a trip lever pivotally mounted on said arm and in removable engagement with the ratchet wheel on the handle and the upper end of the rod, said trip lever being actuated by reverse movement of the handle due to back-firing of the engine, resilient means for facilitating the disengagement of the rod from the ratchet wheel on the shaft when the trip has been actuated, and means for resetting said rod.

In testimony whereof I affix my signature in presence of two witnesses:

LUDY W. WOOLWINE.
